SOUND EMITTING DEVICE

Application filed June 15, 1929. Serial No. 371,237.

Our invention relates to loud speakers of the type adapted to be employed in connection with radio-receiving sets, sound amplifying apparatus, and the like, and has among its other objects the production of devices of the kind described that are compact, durable, simple in construction and efficient.

A particular object of the invention is to provide a device of the kind described that will reproduce sound without distortion thereof.

Another particular object of the invention is to provide an improved loud speaker comprising parts which may be quickly and easily assembled with each other.

Still another particular object of the invention is to provide an improved magnetizing structure for loud speakers employing such structures.

Many other objects and advantages will become apparent as this description progresses, reference being had to the accompanying drawings, wherein:

Figure 1 is a central vertical section taken through a loud speaker embodying the invention.

Fig. 2 is a section taken on line 2—2 of Fig. 1.

Fig. 3 is a section taken on line 3—3 of Fig. 2.

Fig. 4 is a perspective view of a part of the improved magnetizing structure of the loud speaker shown in Fig. 1.

Fig. 5 is a side elevation of the blank from which one of the laminations, shown in Fig. 4, is made, and

Fig. 6 is a perspective view of one of a plurality of bars which are preferably employed in the improved magnetizing structure.

Referring to the drawings wherein we have shown a preferred form of the invention embodied in a loud speaker, the reference character 10 designates generally an improved magnetizing structure having an annular magnetic field 11 in which a winding 12 is movably mounted, the winding 12 being operatively connected by a sleeve 13 to a diaphragm 14, the diaphragm 14 preferably comprising a conical portion 15, preferably formed from paper or any other suitable ma-

terial, the base or larger end of the conical portion 15 being secured to an annular ring 17 which is preferably formed from relatively flexible material, such as soft leather.

The outer periphery of the ring 17 is preferably clamped between a diaphragm supporting member 18 and a ring 19, the ring 19 being secured to the supporting member 18 by bolts 20, or the equivalent. The supporting member 18 preferably comprises an apertured frusto-conical portion 22 and an integral disc portion 23 provided with a plurality of apertures through which a plurality of bolts 25 project.

As best shown in Fig. 4, our improved magnetizing structure 10 preferably comprises a plurality of laminations 26, 26a, 27a and 27. These laminations are preferably L-shaped so that each lamination comprises two portions extending at right angles to each other. One portion of each of the laminations extends rearwardly, as illustrated in Figs. 2 and 4, these rearwardly extending portions being secured to each other by rivets 28, or the equivalent. The rearwardly extending portions of the laminations 26, 26a, 27a and 27 provide E-shaped portions of which the central arm forms a pole piece 29 which is preferably of rectangular cross-section. The other portions of the laminations extend outwardly and at right angles to the E-shaped portions and are arranged to surround the pole piece 29. This construction is accomplished by providing substantially U-shaped slots 32 in the laminations, as best illustrated in Fig. 5, wherein the blank for the lamination 26 is shown. The dotted lines 33 in Fig. 5 indicate the line along which the blank is bent so that the lamination will comprise two portions extending at right angles to each other.

Disposed around the pole piece 29 and preferably engaging the corners thereof is a sleeve 35 of magnetic material, and inserted between the pole piece 29 and the sleeve 35 are a plurality of bars 36, also formed of magnetic material. The front end 37 of the sleeve 35 is preferably of reduced diameter, and is aligned with a pole piece 38 which has an aperture 39 disposed concentrically with re-

spect to the sleeve 35. It will be noted that the annular magnetic field 11 is formed between the pole piece 38 and the forward end 37 of the sleeve 35.

5 Disposed around the sleeve 35 and carried thereby is a sleeve 40 formed of a non-magnetic material and disposed around the sleeve 40 is a winding 42 connected to any suitable source of electrical energy so that the annular magnetic field 12 will be relatively intense. The sleeve 40 functions as a short circuited secondary winding with respect to the winding 42 and eliminates some of the high frequency currents which otherwise would cause 10 a hum in the loud speaker.

It will be noted that the bolts 25 project through apertures 44 provided in the laminations 26, 26a, 27a and 27 and that they project through apertures 45 and 46 provided in a 20 frame member 47, the apertures 46 being formed in inwardly extending integral flanges 49 formed upon the frame member 47. The inwardly extending flanges 49 are preferably positioned between the pole piece 38 and the disc portion 28 of the diaphragm supporting member 18.

Preferably carried by the bolts 25 is a supporting member 50 which is preferably stamped from relatively thin flexible sheet metal, the sheet metal being also relatively 30 resilient. As indicated in Figs. 2 and 3, the member 50 is preferably rectangular in shape, and preferably comprises a flange 52 extending around its entire periphery. The member 50 is preferably provided with a plurality of slots 53 which form arms 54 that are formed integral with a collar 55 secured to the sleeve 13. Nuts 58 upon the bolts 25 space the member 50 from the disc portion 23 40 and the member 50 is clamped between the nuts 58 and nuts 60 which are also screw-threaded upon the bolts 25.

The operation of the above described device is substantially as follows: The winding 42 is 45 connected to any suitable source of electrical energy so that a relatively intense annular field will obtain between the pole piece 38 and the sleeve 35. The winding 11 is connected to a source of telephonic current, or the like, and this current reacts with the magnetic field in such manner that the winding 11 and the sleeve 13 vibrate and impart these vibrations to the diaphragm 14 which translate them into sound.

55 While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as possible, in view of the prior art.

What we claim as new is:

1. A device of the kind described comprising a magnet member formed from a plurality of L-shaped laminations having U-shaped slots cut therein to form a pole piece, a second pole piece having an aperture alined with the first-mentioned pole piece to provide a magnetic field between the pole pieces, a diaphragm, and means reacting with said field for actuating said diaphragm. 70

2. A device of the kind described comprising a magnet member formed of a plurality of laminations bent to form L-shaped pieces, said laminations having substantially U-shaped slots formed therein to provide a pole piece, a second pole piece fixed with respect to the first-mentioned pole piece to provide a magnetic field between said pole pieces, a diaphragm, and means reacting with said field for actuating said diaphragm. 80

3. A device of the kind described comprising a magnet formed of a plurality of laminations, said laminations having substantially U-shaped slots formed therein to provide a pole piece, a tube of magnetic material disposed around said pole piece, a second pole piece disposed around said tube to provide a magnetic field between itself and said tube, a diaphragm, and means reacting with said field for actuating said diaphragm. 90

4. A device of the kind described comprising a magnet formed of a plurality of laminations, said laminations having substantially U-shaped slots formed therein to provide a pole piece of substantially rectangular cross-section, a tube of magnetic material disposed around said pole piece, a second pole piece disposed around said tube to provide a magnetic field between itself and said tube, a diaphragm, and means reacting with said field for actuating said diaphragm. 100

5. A device of the kind described comprising a magnet member having a laminated pole piece of substantially rectangular cross-section, a tube of substantially circular cross-section and formed of magnetic material disposed around said pole piece, a second pole piece co-operating with said tube to provide an annular magnetic field between itself and said tube, a diaphragm, and means reacting with said field for actuating said diaphragm. 110

6. A device of the kind described comprising a magnet member having a laminated pole piece of substantially rectangular cross-section, a tube of substantially circular cross-section and formed of magnetic material disposed around said pole piece, bars of magnetic material inserted between said pole piece and said tube, a second pole piece co-operating with said tube to provide an annular magnetic field between itself and said tube, a diaphragm, and means reacting with said field for actuating said diaphragm. 120

7. In a device of the kind described, a magnet member comprising a plurality of aper- 130

tered laminations forming a pole piece, each lamination being bent to have two portions disposed normal to each other, like portions of the laminations being all secured to each other and the other like portion thereof being disposed extending outward in opposed relation and surrounding said pole piece, a second pole piece surrounding the first-mentioned pole piece to provide an annular magnetic field, a diaphragm, and means reacting with said field for actuating said diaphragm.

8. In a device of the kind described, a magnet member comprising a plurality of apertured laminations forming a pole piece, each lamination being bent to have two portions disposed normal to each other, like portions of the laminations being all secured to each other and the other like portions thereof being disposed extending outward in opposed relation and surrounding said pole piece, a sleeve of magnetic material surrounding said pole piece and carried thereby, a second pole piece surrounding said sleeve to provide an annular magnetic field between itself and said sleeve, a diaphragm, and means reacting with said field for actuating said diaphragm.

9. In a device of the kind described, a magnet member comprising a plurality of apertured laminations forming a pole piece of substantially rectangular cross-section, each lamination being bent to have two portions disposed normal to each other, like portions of the laminations being all secured to each other and the other like portions thereof being disposed extending outward in opposed relation and surrounding said pole piece, a sleeve of magnetic material disposed around said pole piece, bars of magnetic material inserted between said sleeve and said pole piece, a second pole piece surrounding the sleeve to provide an annular magnetic field between itself and said sleeve, a diaphragm, and means reacting with said field for actuating said diaphragm.

10. In a device of the kind described, a magnet member comprising a plurality of apertured laminations forming a pole piece, each lamination being bent to have two portions disposed normal to each other, like portions of the laminations being all secured to each other and the other like portions thereof being disposed extending outward in opposed relation and surrounding said pole piece, a sleeve of magnetic material disposed around said pole piece, a winding around said pole piece, a second pole piece surrounding the first-mentioned pole piece to provide a magnetic field, a diaphragm, and means reacting with said field for actuating said diaphragm.

11. In a device of the kind described, the combination with a magnet member formed of laminations and having a substantially E-shaped portion of which the middle arm forms a pole piece, parts of said laminations

at the free end of said pole piece extending outwardly at right angles to said E-shaped portion, of a second pole piece secured to said parts of said laminations and disposed around the first-mentioned pole piece to provide a magnetic field between the pole pieces, 70 a diaphragm, and means reacting with said field for actuating said diaphragm.

12. In a device of the kind described, the combination with a magnet member formed of laminations and comprising an E-shaped portion of which the middle arm forms a pole piece, parts of said laminations being disposed at right angles to said E-shaped portion, of a sleeve of magnetic material on said pole piece, a second pole piece secured to said parts of said laminations and disposed around said sleeve to provide an annular magnetic field between the first-mentioned pole piece and said second pole piece, a diaphragm, and means reacting with said field for actuating said diaphragm.

13. In a device of the kind described, the combination with a magnet member formed of laminations and comprising an E-shaped portion of which the middle arm forms a pole piece, parts of said laminations being disposed at right angles to said E-shaped portion, of a sleeve of magnetic material on said pole piece, a second pole piece secured to said parts of said laminations and disposed around said sleeve to provide an annular magnetic field between the first-mentioned pole piece and said second pole piece, a diaphragm and a flexible member carried by said parts of said laminations for supporting the diaphragm, and means reacting with said field for actuating said diaphragm.

14. A device of the kind described comprising a laminated magnet member having a laminated pole piece, a second pole piece surrounding the first-mentioned pole piece to provide an annular magnetic field between said pole pieces, a sleeve of non-magnetic metal disposed around said laminated pole piece, a winding around said sleeve, a diaphragm, and means reacting with said field for actuating said diaphragm.

In testimony whereof, we have hereunto set our hands this 5th day of June, 1929.

H. KARL BOUVIER.
FREELAND WELLS.
